OLIVER J. MARSHICK, OF DETROIT, MICHIGAN.

ELECTRIC REVERSING MECHANISM.

1,364,507.

Specification of Letters Patent.

Patented Jan. 4, 1921.

Application filed July 12, 1919. Serial No. 310,443.

To all whom it may concern:

Be it known that I, OLIVER J. MARSHICK, a citizen of the United States, residing at Detroit, county of Wayne, State of Michigan, have invented a certain new and useful Improvement in Electric Reversing Mechanism, and declare the following to be a full, clear, and exact description of the same, such as will enable others skilled in the art 10 to which it pertains to make and use the same, reference being had to the accompanying drawings, which form a part of this specification.

This invention relates to reversing mechanism especially adapted for metal treating furnaces of the rocking or rotating type, and has for its object an improved arrangement of parts whereby the direction of rotation of the furnace drum is automatically reversed after a certain degree of rotation has been accomplished, and whereby this may be manually adjusted for a lesser or a greater degree of rotative movement of the drum, as, for example, during various stages in the 20 process of melting, or when the emptying of the furnace drum through the pouring spout is desired. The same mechanism and principles of operation can, however, be applied to other uses, as for example, the actuation 25 of a churn, a tumbling barrel, or a washing machine and I desire the scope of this disclosure to be considered accordingly.

In the drawings:

Fig. 1 is an end elevational view of a 30 rotatable furnace drum, with my improved reversing mechanism in position with respect thereto.

Fig. 2 is an elevational view, largely in section, of the operative parts of my improved mechanism, with the inclosing shell removed from the side, and shown in section only about the edges of the figure.

Fig. 3 is a sectional elevation, taken along the line 3—3 of Fig. 2.

Fig. 4 is a sectional detail of one of the spring latch or pin members by which the limiting switch arms are held in desired relation to the inclosing casing and to one another.

13 represents a refractory lined furnace drum, about whose periphery engage track members 14, which rest upon the complementarily positioned roller members 15, journaled in the pivoted brackets 17^a which rise from the struts 17. The furnace drum

is also encircled by the toothed ring 16, which is operatively connected, either directly or through the gear members 18^a, 18^b and 18^c, with the idler pinion 18, whose supporting bearing or pin 19 is fixed near the 60 edge portion of one of the side plates of the casing or shell 20. The casing 20 is supported in suitable relation to these parts by the branch strut 21.

The teeth of the large gear wheel 22 65 within the shell 20 mesh with those of the idler pinion 18, the gear wheel being rotatably journaled adjacent one of the side covering plates of the casing 20, on the shaft 23; access to the interior of the shell 20 is 70 afforded by the hinged door 24, or if desired, by the removal of one of the end covering plates of the shell 20. Projecting from the relatively exposed side of the large gear wheel 22 is a stud 25 whose engagement 75 against the adjustable stop members, now to be described, brings about the shifting in the position of the parts that causes the reversal of the direction of rotation of the entire mechanism.

Journalized upon the shaft 23 are a pair of radial arms 26 and 36, the arm 26 being keyed thereto, whereas the arm 36 rises from a sleeve 37 which rotatably engages thereabout. Connected with the outer end of the 85 shaft 23 and sleeve 37 respectively are external adjusting arms, 26^a and 36^a the spring-held stop pins 28 and 38 of each of which are adapted to engage in some one of the series of holes 27 in the adjacent outer face 90 of the casing. In the outer end of each one of the interior arms 26 and 36 respectively is journalized the shaft 29 (or 39) of the forked jaw member 30 (or 40), so positioned as to its distance from the central axis of the 95 shaft 23 that when the large gear wheel 22 rotates sufficiently in either direction, one or the other of them will be engaged by the stud 25. The arms having been so placed as to the series of holes 27 that when either 100 one of these forked jaw members 30 or 40 is engaged by the stud 25, the tilting or rotation of the furnace drum has nearly reached its intended limit, the momentum or coasting thereof serves to carry the large 105 gear wheel 22 and consequently its stud 25 slightly farther. The first tilting of the forked jaw member about its axis will result in turning away the drum contact 31 (or 41) thereof about the axis of the shaft 29 (or 39) 110

2
 as a center from contact with the first set of contact fingers 32 (or 42), and this further swing of the large gear wheel 22 serves to turn the forked jaw member still farther about its axis until its drum contact 31 (or 5 41) engages the second set of fingers 33 (or 43), when the restoration of the circuit's completeness being effected, (though through a different wire path) the rotative travel of 10 the parts in the opposite direction is begun. This continues until the swing of the large gear wheel 22 causes the stud 25 to engage the other one of the forked jaw members 30 or 40 from the last engaged by it, when the 15 same breaking of one set of contacts and making of another set creates a new path for, and direction of, the actuating current, which starts the train of gear wheels in rotation in the opposite direction once more. 20 The size of the arc thus traversed is determined by the angular distance between the two radial arms 26 and 36, which in turn is manually regulated by the positioning in the holes of the arc 27 of the spring held 25 pins 28 and 38 in the ends of the outside adjusting arms. When the metal components are first put into the furnace, and before they are even partly molten, I often find it 30 advantageous to permit a much shorter arc of oscillation than when the contents of the furnace drum are relatively fluid. Ordinarily an oscillation of not to exceed about 170° is the maximum that is desirable, except when the molten metal is ready for 35 pouring, when it becomes desirable to turn the furnace so far over that the pouring spout gradually approaches the very bottom. The position or spread of the adjusting radial arms 26 and 36 for this pouring 40 position may be roughly said to be the arc of 270° indicated by the presence of the holes 27 in Fig. 1, whereas the extreme oscillatory swing for the period of melting would be represented by slightly less than the 180° 45 lying above the horizontal diametrical line. The tilting of the furnace for this pouring operation may be effected by the positioning of these radial arms as just described and allowing the furnace to swing to this limit 50 accordingly, or by shutting off the alternating mechanism entirely and resorting to the use of a hand switch.

Each set of contact brushes has insulated wires leading from it to the switchboard 55 through some one of the binding posts 34. And, if desired, a suitable number of insulating shields 44 may be arranged about the shaft 23 so as to space from one another, and thus more effectively insulate, the current 60 wires 35 and 45 from one another as they lead from the terminals of their respective brushes toward some one of the several binding posts 34, and thence to the several control switches with which the actuating motor 65 is connected. The jaw members 30 and 40

not functionally active while the mechanism is being operated under the control of a hand switch, are often useful in the capacity of limiting switches, serving to prevent damage to the mechanism in case the attendant neglects to stop the pouring switch contact at just the proper time.

What I claim is:

1. In a reversing mechanism, in combination with a pair of adjustable limiting members, a plurality of diversely connected contact members carried by each of said limiting members, a rotatable member operatively connected with the mechanism whose intermittent reversal of movement is desired, and means carried by said rotatable member in position to engage said limiting members at each end of its intended path of travel, thereby effecting a rearrangement of the electrical circuits of which said contact members are parts.

2. In a reversing mechanism, the combination of a rotatable member operatively connected with an external member, a pair of pivoted arms capable of adjustment 75 to each other and to the mechanism as a whole, a plurality of circuit terminals carried on each of said pivoted arms, and a rockable member carried by each of said pivoted arms in position to be engaged by a projecting portion of said rotatable member at each end of its intended path of travel, thereby breaking its previous contact with certain of said circuit terminals and making contacts with others.

3. In a reversing mechanism, the combination, with an oscillatory member operatively connected with an external member whose limited rocking is desired, of a pair of adjustable contact members each capable of 105 limited rotative movement when engaged by said oscillatory member, and a plurality of circuit terminals appurtenant to each of said adjustable contact members, certain of which are adapted to be rendered inactive and the 110 previously inactive others of which are adapted to be placed in circuit by the engagement thereagainst of their contact member when rocked.

4. A reversing mechanism, having in combination a pair of adjustable stop members, supporting members therefor in whose ends said stop members are journaled in position for limited rotative movement, a plurality of series of circuit terminals certain of 1 which are adapted to be rendered inactive and certain others of which are adapted to be placed in circuit by the rocking movement of their adjacent stop members, and a rotatable member operatively connected with an external mechanism, adapted to travel along a path whose limits are determined by the positions of said stop members and upon engaging with either to actuate it relatively to its neighboring circuit terminals.

5. A reversing mechanism, having, in combination with a plurality of stop members, radially arranged support members wherein said stop members are journaled, a plurality of circuit terminals certain of which are normally in contact with one or the other of said stop members and certain others of which are adapted to be placed in circuit in succession to the first named series when their stop member is actuated, and an oscillatory engaging member operatively connected with an external mechanism, adapted to touch one of said stop members near each end of its possible path of travel, thereby actuating it relatively to its neighboring circuit terminals.
6. In a reversing mechanism, the combination, with an oscillatory engaging member operatively connected with an external mechanism, of a pair of oppositely disposed movable stop members capable of individual adjustment as to position, and a plurality of circuit terminals appurtenant to each of said stop members, certain of each set being normally in circuit with their stop member 25 and being adapted to be disconnected therefrom and connected with the normally inactive members of the set when the stop member is engaged by the oscillatory engaging member.
7. In a reversing mechanism, the combination of a plurality of series of circuit terminals, a pair of adjustable stop members with one or the other of which each circuit terminal is associated, and an oscillatory member 35 adapted to engage said stop members alternatingly, thereby effecting a rearrangement of their circuit connections.
- In testimony whereof I sign this specification in the presence of two witnesses.
